UNITED STATES PATENT OFFICE.

FRANCIS J. MEAGHER, OF NEW YORK, N. Y.

DOOR CONTROLLER.

Application filed March 13, 1923. Serial No. 624,718.

To all whom it may concern:

Be it known that I, FRANCIS J. MEAGHER, a citizen of the United States, residing in the city of New York, borough and county of Queens, in the State of New York, have invented a certain new and useful Improvement in Door Controllers, of which the following is a specification.

The invention relates to mechanism for opening and closing doors and more particularly for operating elevator shaftway doors.

The object of the invention is to provide a simple, easily operated door opening device for sliding doors which will close the door automatically when released, and operate quickly and quietly. Another important object is to provide means whereby the partly closed door is held against any attempt by persons on the corridor side to re-open it.

20 A further object is to provide means for disconnecting the device to allow the sliding door to be swung outwardly when required. Another important object is to provide means whereby the controller can be easily 25 and reliably installed without requiring alterations in or special construction of the doorframe or shaft to receive it.

The invention consists in certain novel features and details of construction and arrangement by which the above and other objects are attained, to be hereinafter described and claimed.

The accompanying drawings form a part of the specification and show the invention 35 as it has been carried out in practice.

Figure 1 is an elevation showing a sliding shaftway-door equipped with the improved controller, seen from the interior of the shaft.

40 The remaining figures are on a larger scale and show portions.

Figure 2 is an elevation, partly in vertical section, showing the keeper and its connections to the door, and the door-operating lever slidably received in such keeper.

45 Figure 3 is a transverse section taken on the line 3-3 in Figure 2.

Figure 4 is a section taken longitudinally of the lever and keeper, on the line 4-4 in 50 Figures 2 and 3.

Figure 5 is a horizontal section taken on the line 5-5 in Figure 2.

55 Figure 6 is a side elevation of the fixed bracket to which the lever is connected, and other connected parts, partly in vertical section.

Figure 7 is a plan or top view of the bracket.

Figure 8 is a face view of the same.

Figure 9 is a transverse section taken on 60 the line 9-9 in Figure 6.

Figure 10 is a transverse section taken on the line 10-10 in Figure 6.

Similar reference numerals indicate the 65 same parts in all the figures.

The door 12 is suspended from hangers 13 engaged with a horizontal track 14 and slides horizontally in the usual manner to open and close the elevator shaftway opening. The saddle or sill of the doorframe is 70 marked 15 and the jambs or bucks 16.

At the lower corner of the doorframe farthest from the door-opening, is secured the master bracket 17 fastened by screws at 75 19 to the buck 16, and having a horizontally projecting foot 18 similarly fastened to the saddle 15 and is thus held firmly in position. Near the upper end of the vertical portion of the bracket 17 is an outwardly projecting 80 semicircular lug 20 in which is a centrally located pin 21 serving as a pivot for a bifurcated arm 22 the legs 23 of which inclose the lug 20 and are mounted on the pin.

The body of the arm is U-shaped, see Figure 10, and has a partition or abutment 24 85 near the lower end provided with an aperture 25 through which extends a chain 26 fastened at one end to a pin 27 in the vertical reinforcing flanges 28 of the bracket 17, and at the other to a rod 29 standing inclosed 90 in the arm 22; the rod is encircled by a helical compression spring 31 abutting at the lower end against the partition 24 and at the upper end against a nut 32 on the screw-threaded outer end of the rod.

95 The chain 26 lies tangentially to the curve of the lug 20 and, with the rod 29, is thus maintained axially in the arm 22 as the latter is swung on the pin 21. The expansive force of the spring 31 tends to swing the arm 100 outwardly and downwardly and the compression of the spring is adjusted by the nut 32.

Set transversely of the legs 23 below the chain 26 is a pin 33 to which is attached the 105 plunger rod 34 of a checking cylinder 35 pivotally connected at the lower end to the foot 18 of the bracket 17 and serving to retard the outward movement of the arm 22 as will be understood. The rapidity of the outward swing is varied as required by a flow-controlling screw 57 set in the upper head.

of the cylinder 35 and operating as usual.

Secured in the arm 22 and covering its open face is the door-operating lever 36 of which the arm 22 is a continuation; it is 5 channel-shaped in cross-section with its closed face presented to the shaftway side of the door 12. The channel form affords the desired light but eminently stiff quality necessary in the lever.

10 On the door 12, preferably at the side nearest the bracket 17, is fastened a tablet 37 having a vertical slot at 38 in which is received a long boss 39 on a plate 40. The plate is held by a removable bolt 41 extending through the boss and through straps 56 on the tablet.

15 Projecting from the opposite face of the plate 40 is a stud 42 serving as a pivot for a trough-like hollow keeper 43 receiving and 20 guiding the lever 36 extending slidably therethrough. Its flanges 44 and 45 project outwardly from the plate and receive a cover 46 applied thereon, thus inclosing the lever, the flanges 47 and 48 of which project 25 inwardly as shown. The keeper 43 is slightly triangular in shape and is arranged to be oscillated vertically on its stud 42 relatively to the lever 36 by a handle or pull 49 projecting from the lower end of the 30 flange 45.

35 Mounted on the interior face of the flange 48 of the lever, within the keeper and extending longitudinally of the lever as far as may be required, is a narrow ratchet-bar 50 having its teeth presented upwardly and arranged to be engaged by the angular nose of a dog 51, fixed upon the inner face of the keeper 48, when the latter is in the depressed position shown in Figure 2, and to 40 be disengaged when the keeper is lifted to the position shown in dotted lines in the same figure by the upward movement of the handle 49.

45 On the outer end of the stud 42 and lying between the ratchet-bar 50 and the face of the lever 36, is a guide-roller 52 having a diameter nearly equal to the distance between the flanges 47 and 48 of the lever and serves with either of such flanges as may 50 contact therewith in the sliding movements of the lever through the keeper in lessening the friction, and 53 is a similar but smaller antifriction roller mounted on a pivot pin 54 on the keeper, arranged to contact with 55 the inner face of the lever-flange 47 when the keeper is thrown to disengage the dog 51.

60 The operation is as follows:—Assuming the door to be closed and locked by the engagement of the dog with a ratchet-tooth, as shown by the full lines in Figure 1, and it is desired to open the door, the attendant on the elevator car, not shown, grasps the handle or pull 49 and moves the keeper 43 65 upwardly at its lower end to free the dog

51 from the ratchet 50, this movement throws the roller 53 into contact with the flange 47 of the lever 36 and thus supports it with liberty to slide freely; a continued pull on the keeper in the direction to open 70 the door slides the latter to the position shown in dotted lines in Figure 1 and exposes the door opening. In this swing of the lever to the approximately vertical position the chain 26 follows the contour of the 75 lug 20 and is correspondingly shortened, thus compressing the spring 31. The same movement of the arm 22 draws the plunger-rod 34 from the checking cylinder 35. The door is now open and will remain open so 80 long as held by the attendant in opposition to the closing action of the spring 31.

On releasing the pull on the keeper 43 the door will automatically close by the force of the spring 31 acting through the lever 36, 85 the rapidity of the closing movement being governed by the restricted flow of the fluid in the checking cylinder.

The release of the keeper permits it to drop by gravity and present the dog 51 in 90 position to engage the teeth of the ratchet-bar 50; the dog on reaching the bar will ride idly over the teeth but in position to engage each in its passage. This arrangement precludes any reverse movement of the door 95 and effectually prevents re-opening by anyone on the corridor side of the door, and when the door is completely closed it is securely locked by the dog against opening from such side, thus avoiding the danger of 100 accidents due to attempts to pass the partially closed door.

The plate 40 may be secured directly to the door if the latter be of the simple sliding type. With the tablet 37 and its separable connection to the plate by the boss 39 and removable bolt 41 the controller may be disconnected from the door and the latter with its supporting portion be swung on 105 hinges, not shown, into the corridor to afford the full opening from the corridor to 110 the car in the usual manner.

The door may be opened from the corridor side when required under exceptional circumstances, by inserting a key or other 115 winged implement, not shown, through a keyhole 55 provided for the purpose in the door immediately adjacent the keeper, and turning such key in the direction to engage with and lift the keeper and thus free the 120 dog 51 from the engaged tooth on the ratchet-bar 50, as will be understood.

The opening and closing movements of the parts are practically frictionless and noiseless, the rollers 52 and 53 insuring 125 smooth easy traverse of the lever through the keeper.

By attaching the bracket 17 directly to the saddle and buck the device is reliably held and the necessity for alterations and 130

special provisions to permit installation are avoided, and as the mechanism occupies but little space such installation is greatly simplified with a corresponding reduction in cost.

The parts within the keeper and arm are concealed and protected, and the joints are constructed to avoid wear and insure stability and alinement. The construction of the 10 spring closing mechanism and manner of connecting the checking mechanism are such as to permit installation under all conditions.

The controller is simple, durable, efficient 15 and inexpensive, and the parts are easily accessible for inspection and repairs.

Modifications may be made in the forms and proportions in adapting the controller to various types of doors and conditions of 20 service, and parts of the invention may be used without the whole.

I claim:—

1. In a device of the character set forth, a bracket adapted to be secured to the buck of a doorframe and having a foot rigid therewith and adapted to be secured to the saddle, and a door-operating lever pivotally mounted on said bracket and adapted for attachment to a sliding door.

2. In a device of the character set forth, a bracket adapted to be secured to the buck of a doorframe and having a rigid angled foot adapted to be secured to the saddle thereof, a door-operating lever pivotally mounted on said bracket, a spring carried by said lever, connections from said spring to said bracket, and means for increasing the tension of said spring by a movement of said lever in one direction.

3. In a device of the character set forth, a bracket adapted to be secured to the buck of a doorframe and having a rigid angled foot adapted to be secured to the saddle thereof, a lug on said bracket having a

curved outer face, a door-operating lever 45 pivotally mounted on said lug, a spring carried by said lever, and a chain connecting said spring to said bracket and arranged to lie tangentially to such curved face.

4. In a device of the character set forth, 50 a bracket embodying rigid substantially right angled members, a lug thereon having a curved outer face, a hollow lever having legs pivotally secured to said lug, a partition in said lever, a spring within the latter, a rod inclosed in said spring and having a nut, said spring abutting at one end against said partition and at the other against said nut, a check connected with said bracket adjacent its angle and with 55 said lever adjacent its pivot and a chain connecting said rod and bracket and arranged to lie tangentially to such curved face.

5. In a device of the character set forth, 60 a bracket having rigid substantially right-angled members adapted to be secured to the buck of a doorframe and to the saddle thereof, a door-operating lever pivotally mounted on said bracket, a spring carried by said lever, connections from said 65 spring to said bracket, means for increasing the tension of said spring by a movement of said lever in one direction, and checking means connected to said lever and to said foot and arranged to retard the movement 70 of said lever in the opposite direction.

6. A bracket for the purpose set forth embodying an upright member adapted to be secured to the buck, and a rigid substantially right-angled foot adapted to rest upon 80 and be secured to the saddle, said bracket being formed near its upper end and adjacent its angle with lugs to receive pivots of a sliding-door actuating arm and a check respectively.

In testimony that I claim the invention above set forth I affix my signature.

FRANCIS. J. MEAGHER.
